UNITED STATES PATENT OFFICE.

CHRISTIAN F. PAUL, JR., OF PEEKSKILL, NEW YORK.

PISTON.

1,159,530.

Specification of Letters Patent.

Patented Nov. 9, 1915.

Application filed May 11, 1914. Serial No. 837,703.

To all whom it may concern:

Be it known that I, CHRISTIAN F. PAUL, Jr., a citizen of the United States, residing at Peekskill, in the county of Westchester 5 and State of New York, have invented certain new and useful Improvements in Pistons, of which the following is a full, clear, and exact description.

This invention relates to "piston rings", 10 for maintaining a substantially fluid-tight joint between a piston and the cylinder in which the same works, and its chief object is to provide an improved construction of simple character which shall be simple and 15 inexpensive to manufacture and withal thoroughly effective in use.

To this and other ends the invention consists in the novel features of construction and combinations of elements hereinafter 20 described.

The preferred form of the invention is illustrated in the accompanying drawings, in which—

Figure 1 is a perspective view of the piston, removed from its cylinder. Fig. 2 is a 25 section on the plane of line 2—2, and Fig. 3 is a section on the plane of line 3—3 of Fig. 1. Fig. 4 is a longitudinal section of the piston and a portion of the cylinder in which 30 it works, the section being in a plane at right angles to Fig. 1.

The piston 10 is provided on its sides with a number of superposed angularly staggered transverse slots or recesses to receive arc-shaped packing-pieces or segments which 35 are urged outwardly by suitable springs and thereby caused to bear yieldingly on the contiguous walls of the cylinder 11. The precise number and arrangement of slots 40 and packing-pieces used are immaterial, but in the embodiment illustrated, I provide twelve packing-pieces and of course the same number of slots to receive them. In the form shown, the uppermost slots 12, 13 are 45 in the same plane at right angles to the axis of the piston and are diametrically opposite each other, with their inner edges substantially parallel to each other. Immediately below are similar slots 14, 15, preferably 50 of the same size as the former, and displaced or staggered angularly 90° therefrom. Below the slots 14, 15, are similar slots in vertical alinement with the slots 12, 13; while 55 below these latter is another pair of slots, alined vertically with the slots 14, 15. The arrangement described is repeated as often

as desired, so that above or below each slot is a slot displaced or staggered angularly to an extent depending largely upon the angular extent of the slots themselves. If 60 two slots in each plane are used, arranged diametrically opposite each other, each somewhat greater than 90° in extent an angular displacement of 90° between centers gives satisfactory results. The packing- 65 pieces 16 fit the slots closely, but are freely movable therein. Their curved outer edges are preferably of the same radius as the piston 10, and the pieces themselves are preferably of such width (radially) that when 70 pressed into the slots they will substantially fill the same.

The springs employed to press the curved packing-pieces outwardly may be of any suitable kind, but the simple leaf type shown 75 at 17 in Figs. 2 and 3 gives as good results as any in practice. These springs are formed with a lobe or bend 18 at the center, to fit a similarly shaped or "undercut" notch 19 in the inner edge of the packing-piece. 80 The ends of the springs then bear on the inner surfaces of the slots. When this type of spring is used, space should be provided for the ends or wings of the springs when the packing-pieces are pressed in until their 85 curved surfaces are flush with the surface of the piston. For this purpose the slots can be made slightly deeper than the radial width of the packing-pieces, as indicated in Figs. 2 and 3. For the best results, it is desirable 90 that the plane of the bottom or lower surface of each slot coincide with the plane of the upper surface of the slot or slots next below, that is: each slot should open into the slot or slots immediately below, so that 95 each packing-piece will be in contact, at one or both ends, with the piece next above or below, as the case may be. This construction is illustrated in Fig. 1, where it is seen that each piece is in contact at its ends with 100 the piece above or below.

The preferred piston construction and the cylinder are shown assembled in Fig. 4, which represents the condition when the parts are substantially worn, the packing- 105 pieces being then flush with the surface of the body of the piston. As the piston reciprocates (and in some cases rotates also) in the cylinder, there will at first be some wear on the piston body as well as on the 110 packing-pieces, but the latter soon take all the wear and hence soon come to fit the cyl-

inder perfectly, even if they did not so fit originally. In short, the mutual wear of the cylinder and packing-pieces maintains, or produces and maintains, a perfect fit. It 5 will also be observed that if the piston rotates as well as reciprocates, the cylinder and piston cannot wear into oval form, even when operated on a horizontal axis, since the rotation of the piston, in conjunction 10 with the constant outward pressure of the packing-pieces, will distribute the wear with substantial equality and hence keep the cylinder circular in cross section.

It is to be understood that the invention 15 is not limited to the specific construction herein illustrated and described, but can be embodied in other forms without departure from its proper spirit and scope.

What I claim is:

- 20 1. The combination of a cylinder, a piston working therein and having in its sides a plurality of axially superposed recesses offset or staggered angularly, packing pieces movably fitted in said recesses and having 25 their outer surfaces curved in substantial conformity with the inner surface of the cylinder, and springs arranged to press the packing pieces yieldingly against the inner surface of the cylinder.
- 30 2. The combination of a cylinder, a piston working therein and having in its sides a plurality of pairs of diametrically opposite recesses, said pairs of recesses being in different planes perpendicular to the axis of the piston and cylinder and staggered or displaced angularly with respect to each other, packing-pieces movably fitted in the recesses and having their outer edges curved in substantial conformity to the inner 35 surface of the cylinder; and springs arranged to press the packing pieces against the said 40 face of the cylinder; and springs arranged to press the packing pieces against the said inner surface.
- 45 3. A piston having in its sides a plurality

of slots in a plurality of transverse planes, each slot being displaced angularly with respect to the slot or slots in the adjacent plane or planes, outwardly movable packing-pieces fitting the slots and having curved outer edges, and springs arranged to press the packing-pieces outwardly. 45

4. A piston having in its sides a plurality of transverse slots in a plurality of transverse planes, the slot or slots in each plane opening into, and being displaced angularly with respect to, the slot or slots in the adjacent plane or planes, outwardly movable packing-pieces fitting the slots and having curved outer edges, and springs arranged to press the packing-pieces outwardly. 50

5. A piston having in its sides a plurality of pairs of diametrically opposite recesses, said pairs of recesses being in different planes perpendicular to the axis of the piston and cylinder and staggered or displaced angularly with respect to each other, outwardly 60 movable packing pieces mounted in said slots and having curved outer edges and springs attached to the packing pieces at their inner edges and bearing on the inner faces of the slots to press the packing pieces 65 outwardly. 70

6. A piston having a transverse slot in its side, an outwardly curved and outwardly movable packing-piece mounted in the slot and having an undercut recess in its inner edge, and a leaf spring bearing on the inner 75 face of the slot and having a bend fitting the aforesaid notch to connect the spring to the packing-piece.

In testimony whereof I affix my signature 80 in the presence of two subscribing witnesses.

CHRISTIAN F. PAUL, JR.
